UNITED STATES PATENT OFFICE.

WALTER P. MURPHY, OF CHICAGO, ILLINOIS.

RELEASE-RIGGING.

1,084,163.

Specification of Letters Patent. Patented Jan. 13, 1914.

Application filed March 7, 1911. Serial No. 612,964.

To all whom it may concern:

Be it known that I, WALTER P. MURPHY, a citizen of the United States, residing at Chicago, in the county of Cook and State of Illinois, have invented certain new and useful Improvements in Release-Rigging, of which the following is a specification.

The object of my invention is to produce a joint between the hand operated lever and the locking pin lifting lever of a character that will permit the disengagement of the levers for repairs without heating or spreading the metal of either lever.

The further object of my invention is to provide a stop to prevent the accidental displacement or disconnection of the levers; and with these and minor objects in view, my invention consists of the parts and combination of parts as will be hereinafter more fully pointed out.

In the drawing, Figure 1 is a top plan view of the end sill of a car with my invention attached; Fig. 2 is a front elevation of the same, and Fig. 3 is an end elevation of the same with the hand operated lever in section.

The numeral 1 designates the end sill of a car of any approved construction, to which the hand operated lever 2 is secured by suitable clips. The outer end of the lever 2 is provided with a hand crank 3 and its inner end with a crank 4, said crank terminating in an open hook 5, the free end of which is bent up to form a stop 6, said stop being disposed vertically and within the lines of said free end. I have shown the stop as being curved on its end face, as more clearly seen in Fig. 3, as such an outline facilitates the removal of the pin lifting lever from this hook, as will be herein-after described.

The pin lifting lever 7 is provided with the hook 8 at its inner end for engagement with the eye of the locking pin of the coupler and is provided with a closed eye 9 at its outer end, which is at right angles to the hook 8.

To assemble the two levers, the closed eye 9 is placed in a position at right angles to that shown in Fig. 2 and is passed over the stop 6, then over the free arm of the hook 5 and thence passed around to the body of the crank 4 to the position shown in Figs. 1 and 2, in which position the closed eye 9 is on the main body of the crank 4, while the body of the lever 7 rests upon the free

arm of the hook 5, as clearly shown in Figs. 1 and 2, said lever 7 being prevented from disengagement from the hook 5 by the stop 6.

In Fig. 1, I have shown in dotted lines, the maximum movements of the pin lever incident to the movement of the draw bar carrying the coupler in transit. In one of the dotted positions, it will be noted that the lever 7 is locked against the stop 6, while in the other position the closed eye 9 is locked on the crank 4. In Fig. 2, I have shown a maximum position in dotted lines of the pin lifting lever, in which position it will be noted that it is still held from disengagement with the lever 2 by means of the stop 6. The dotted position shown in Fig. 2 is rather extreme for the pin lifting lever, inasmuch as all locking pins drop back somewhat. It will be seen that this construction provides for a lever of this character which is non-collapsible and at the same time will permit the pin lifting lever to remain in its elevated position after lifting the locking pin and also permit the hand operated lever to assume its normal position with the operating handle 3 depending below the car sill. This is important as there is no danger of an accident to the operator or damage to the lifting lever when the cars are brought together in the act of coupling.

In the event that the draw bar of one car breaks away from its fastenings, the pin lifting lever is free to follow it to the extent of the position shown by the outermost dotted lines in Fig. 1, but as soon as it reaches this position, the pin lifting lever becomes locked to and rigid with the crank 4 and its hook 5 and further movement is stopped, which will result in some types of couplers in the locking pin being withdrawn from the coupler and uncoupling the cars, thereby preventing the draw bar from being pulled entirely from under the car and dropping on to the road bed.

In release rigging, it frequently happens that one of the levers becomes damaged and in order to repair the damaged part, it is necessary to take off both of the levers. By my construction, I am enabled to take off either lever separately without disturbing the other. For instance, suppose the pin lifting lever is damaged—all that is necessary is to release it from the locking pin, then bring it to a vertical position, whereupon the closed eye 9 can be slipped around

the open hook 5, and then by turning it at right angles, it can be passed over the stop 6 without removing the hand operated lever 2.

5 The portion 6 limits the backward movement of the rod 7 which is essential to complete lifting of the lock of the couplers. In practice the brackets of rod 2 are located as near the bends of the rod as will allow it to 10 rotate freely and all the movement of the coupler is permitted by placing the hook 8 safely away from the eye of the lock under all service movements and only in case the 15 coupler or draft attachments failed and the coupler pulled excessively forward, would the hook 8 come in contact with the coupler lock eye.

I claim—

1. A hand operated lever having a crank 20 at its inner end and an open hook on said crank, the end of the hook lying parallel to the crank, the hook and the end of said crank forming two substantially parallel members, a pin lifting lever having an eye 25 to engage one of said members, a stop on the other member, said pin lever overlying said other member in proximity to said stop.

2. A hand operated lever for release rig- 30 ging, terminating in an open hook at its

inner end, the free end of said hook being 30 bent at an angle to, but in line with the body of said free end to form a stop in combination with a pin lifting lever.

3. In a release rigging, the combination with a locking pin lifting lever having a 35 closed eye at its outer end, of a hand operated lever terminating in a crank at its inner end, an open hook at the end of said crank, and a stop formed at an angle to, but in line with the body of the free end of said hook, 40 the closed eye of the pin lever being adapted for engagement with the crank of the hand lever and held in locked engagement therewith by said stop.

4. In a release rigging, the combination 45 with a locking pin lever having an eye at its outer end, of a hand operated lever having a crank at its inner end, an open hook at the end of said crank, a stop formed at an angle to, but in line with the free end of 50 said hook, the eye of the lever engaging the crank of the hand lever while the lever is supported on said hook.
